UNITED STATES PATENT OFFICE.

ALBERT W. BRIGHT, OF WASHINGTON, DISTRICT OF COLUMBIA, ASSIGNOR TO THE COLUMBUS GLASS COMPANY, OF LANCASTER, OHIO.

DEVICE FOR CAPPING GLASS CYLINDERS.

1,130,373.

Specification of Letters Patent. Patented Mar. 2, 1915.

Application filed August 2, 1913. Serial No. 782,688.

To all whom it may concern:

Be it known that I, ALBERT W. BRIGHT, of Washington, in the District of Columbia, have invented certain new and useful Improvements in Devices for Capping Glass Cylinders; and I do hereby declare the following to be a full, clear, and exact description of the invention, such as will enable others skilled in the art to which it appertains to make and use the same.

My invention relates to an improvement in devices for capping off glass cylinders, the object being to provide a simple and effective hand tool by which glass cylinders can be accurately and quickly severed or capped off, and it consists in a handle made in two sections each section of which is secured to an end of the heating wire, and means for connecting the two sections of the handle.

My invention further consists in a handle made in two detachable sections, means for connecting an end of the heating wire to each section and means carried by one section for taking up the slack in the wire.

It further consists in a handle composed of two sections, a heating wire connected with each section and means for conducting an electric current to said wire.

It further consists in the details of construction as will be more fully described and pointed out in the claims.

In the accompanying drawings, Figure 1 is a view in longitudinal section of my improvement; Fig. 2 is a view in elevation showing the two sections of the handle separated and Fig. 3 is an edge view.

The handle is preferably rectangular in shape, and is divided longitudinally into two sections as shown in Fig. 2. One section is provided at one edge with tenons 3, which fit in mortises 4 in the other section, and the two sections are also preferably provided with engaging shoulders 5 and 6, which, with the mortises and tenons absolutely prevent any independent movement of either section of the handle. One section also carries the spring latch 7, which engages the keeper 8 in the other section for locking the two sections together, the construction of the latch and keeper being such that, the two parts may be readily connected by simply bringing them into proper posi-

tion and pushing them together, and may be readily separated by a pulling stress applied to the sections.

The handle sections are made of indurated fiber or other suitable non-conducting material, and the section 1 is preferably made hollow so as to contain and conceal the leading-in wires 9 and 10. The wire 9 is connected with the switch block 11, and the other wire 10 is electrically connected with the shank of the latch 7. A wire or other suitable conductor 12 connects the other member 13 of the switch with a metal terminal block 14 at the front end section 1 of the handle 14. This block 14 is grooved at its outer end for the passage of the heating wire 15, one end of which is attached to the screw 16 secured to terminal block 14. This heating wire passes under the lug 17 integral with or secured to the terminal block 18, which is secured to the front end of the section 2 of the handle, and the free end of said wire is connected to the reel 19 on which surplus wire is wound. The block 18 is grooved to permit the wire to pass in an approximately straight line to the reel 19, and the latter is mounted on the arm 20 pivoted at 21 to section 2 of the handle. The keeper 8 is integral with or electrically connected to the terminal block 18, so that when the two sections of the handle are connected, and the switch lever 22 is in contact with the switch member 11 the current for heating the wire 15 will pass from the block 14 to the wire 15; from the latter to the block 18 and from then through the latch 7 back to the leading-in wire 10. The blocks 14 and 18 are insulated from each other, and the construction is such, that, there will be but little space between the wire at the front end of the handle so that approximately the entire cylinder will be encircled by the heating wire 15.

In the use of the device the operator separates the sections and passes one section over the cylinder. This section being suspended from the free end of the wire, straightens out the latter so that it can be readily swung under the cylinder and into a position to be readily grasped by the operator, who then connects the two sections by simply bringing their mating edges into contact. The cylinders vary but slightly in diameter so that the free wire between the

terminal blocks 14 and 18, is usually sufficient to embrace the cylinder, and any variations in size can be taken care of by letting out wire from the reel or winding up the surplus. After the two sections of the handle have been secured together the wire surrounding the cylinder is drawn tightly into contact with the latter, by the operator pulling back on the arms 20 carrying the reel 19, which he may conveniently do with one finger of the hand carrying the handle. After the wire has been properly applied to the cylinder, the switch lever is moved to close the circuit, and the current passing through the wire 15 rapidly heats it, and the heat being communicated to the cylinder causes the latter to break or fracture on the heated line. The heating of the wire causes it to expand, but this expansion is taken care of by the reel which is held under rearward pull by the operator during the capping operation. In order to heat the small portion of the cylinder between the wires at the points 25 where the latter turn into the grooves in the terminal blocks, the operator may shift the handle up or down and thus bring the hot wire into contact with the entire circumference. To make another cut, the handle members are separated and applied as before at the point on the cylinder where the next cut is to be made.

It is evident that many slight changes might be resorted to in the relative arrangement of parts shown and described without departing from the spirit and scope of my invention. Hence I would have it understood that I do not wish to confine myself to the exact construction and arrangement 40 of parts shown and described, but

Having fully described my invention what I claim as new and desire to secure by Letters-Patent, is:—

1. A glass severing tool composed of a 45 two part handle adapted to be separated and united at each operation of the tool, each part having a metal terminal for an electric heating wire, mechanical means for detachably connecting said parts and means 50 for electrically connecting the terminal on one of said parts with a conductor on the other part, when the said parts are mechanically connected.

2. A glass severing tool composed of a 55 two part handle adapted to be separated and united at each operation of the tool, each part having a metal terminal for an electric heating wire, mechanical means for detachably connecting said parts, a heating 60 wire having contact with a terminal on each part, means for electrically connecting the terminal on one part with a conductor on the other part and means for taking up the slack in the wire.

3. A glass severing tool composed of a

two part handle adapted to be separated and united at each operation of the tool, a metal terminal on each part, a heating wire in contact with both of said terminals, conductors carried by one part of said handle, 70 one of said conductors being connected with the terminal on said part, and means for electrically connecting the terminal on other of said part with a conductor on the other part, when the two parts of said handle are 75 in assembled position.

4. A glass severing tool composed of a two part handle adapted to be separated and united at each operation of the tool, means for detachably connecting the two parts, a metal contact piece on each part, a heating wire adapted to encircle the article to be severed and connected with both contact pieces, and electric conductor connected with each contact piece, means carried by the two parts of the handle for electrically connecting the contact piece on one part of the handle with one of the conductors on the other part of the handle when the two parts of the latter are assembled and a 80 switch for closing the circuit through the conductors and heating wire.

5. A glass severing tool composed of a two part handle adapted to be separated and united at each operation of the tool, electric conductors and a switch carried by one part of the handle, a contact piece on each part thereof, heating wire adapted to embrace the article to be heated and contacting with both contact pieces and means adapted when the two parts of the handle are assembled to connect the contact piece on one part to an electrical conductor in the other part.

6. A glass severing tool composed of a 105 two part handle adapted to be separated and united at each operation of the tool, one part carrying electric conductors and a switch and each part carrying a contact piece, a heating wire adapted to embrace the article to be heated and secured at one end to one of said contact pieces and having loose connection with the other, means carrying the other end of the wire and adapted to be moved toward and away from 110 the contact piece with which the heating wire is loosely connected whereby the wire loop may be enlarged and slack in the wire be taken up, means for detachably locking the two parts of the handle together, and means 115 for electrically connecting the contact piece on one of said handle parts with a conductor on the other part when the two parts are brought into assembled position.

7. A glass severing tool composed of a 125 two part handle adapted to be separated and united at each operation of the tool, a heating wire loop projecting beyond the end of said handle when the two parts of the latter are assembled, and adapted to en- 130

circle the article to be cut and connected at one end to one part of the handle and at its other end to the other part, means for taking up the slack in the wire, electrical 5 conductors and a switch carried by one part of the handle, and a contact piece on each part of the handle with which said heating wire is connected and means connecting both contact pieces with said conductors

when the two parts of said handle are in 10 assembled position.

In testimony whereof, I have signed this specification in the presence of two subscribing witnesses.

ALBERT W. BRIGHT.
